(57) **CLAIM**

The ornamental design for a firearm suppressor as shown and described.

DESCRIPTION

FIG. 1 is a perspective view of a firearm suppressor showing the new design.

FIG. 2 is a front view of a firearm suppressor showing the new design.

FIG. 3 is a rear view of a firearm suppressor showing the new design.

FIG. 4 is a longitudinal section view of a firearm suppressor showing the new design.

FIG. 5 is a top view of a firearm suppressor showing the new design.

FIG. 6 is a bottom view of a firearm suppressor showing the new design.

FIG. 7 is a first side view of a firearm suppressor showing the new design; and,

FIG. 8 is a second side view of a firearm suppressor showing the new design.

The broken lines in FIG. 5 depict the sectional cut of FIG. 4 and form no part of the claimed design.

1 Claim, 3 Drawing Sheets
